[57] CLAIM

The ornamental design for stackable container for bottles, as shown and described.

DESCRIPTION

FIG. 1 is a top perspective view of a stackable container for bottles showing our new design;

FIG. 2 is a bottom perspective view thereof;

FIG. 3 is a top plan view thereof;

FIG. 4 is a bottom plan view thereof;

FIG. 5 is a front elevation thereof; the rear elevation being a mirror image thereof;

FIG. 6 is a left side elevation thereof; the right side elevation being a mirror image thereof; and,

FIG. 7 is a fragmentary sectional elevation thereof; taken along line 7—7 of FIG. 3.

FIG. 1**FIG. 2****FIG. 3****FIG. 4****FIG. 5****FIG. 6****FIG. 7**
